Application July 1, 1939, Serial No. 282,449

1 Claim. (Cl. 18—24)

This invention relates to a machine for the treatment of thin tubular rubber articles and the like preferably formed from liquid latex but adopted for other uses as well.

The principal object of the invention is mechanically to eliminate the excess of latex which accumulates on the end of the dipping forms after the dipping operation.

With the foregoing and other objects in view as will appear as the description proceeds the invention resides in the combination and arrangement of parts and in the details of construction hereinafter described and claimed, it being understood that changes in the embodiment of invention herein disclosed may be made within the scope of what is claimed and as more particularly indicated by the variations in scope of the claim.

In the accompanying drawings forming part of this specification:

Figure 1 is a side elevation of a machine embodying the invention.

Figure 2 is an incomplete plan view with certain parts left out to promote clarity.

Figure 3 is an end elevation of the machine.

Figure 4 is a plan section along the line 4—4 of Figure 3.

Figure 5 is an enlarged fragmentary view of the right hand upper portion of Figure 1.

Figure 6 is a fragmentary end section along the lines 6—6 of Figure 5.

Figure 7 is a side elevation of a particular mechanism within the machine, the frame being shown in dot and dash lines, the rest of the machine being omitted for the sake of clarity.

Figure 8 is a plan view of the mechanism shown in Figure 7.

Figure 9 is a detail of the clutch shown in Figure 8 illustrating pawl for holding clutch out of engagement.

Figures 10 and 11 illustrate the method by which the counterbalance is returned to starting position.

Figures 12 and 13 are detail views.

Generally described, the spinner apparatus of this invention receives the form-board *b*, Figure 1, which is slid endwise into the spinner.

The function of this apparatus is to eliminate through centrifugal action, an excess of latex which accumulates on the end of the forms after the dipping operation.

Should this excess be allowed to remain, it would cause an uneven top, and an objectionable tip or globule, of thick rubber on the article, and from a commercial point of view, would lower the 55

quality and saleability of the merchandise. The spinner consists of two guides into which the form boards are pushed alternately, but it is to be understood that a greater number may be employed, by certain modifications of the system. In the present machine, the guides are mounted upon a shaft 180 (degrees) apart, which rotates 2½ times in 4.8 seconds, which is sufficient to accomplish the purpose; however, this speed may 5 be varied by the introduction of the proper gearing ratio in the mechanisms. When the spinner is at rest, a form-board *B* (with forms downward) is pushed into the guide that is directly under the opposite guide, while a form-board 10 (with forms upward) is pushed off the upper guide by the pusher mechanism of the transfer machine, and if for any reason the form boards are not completely pushed on or off the spinner, a safety device incorporated in the spinner mechanism 15 operates to prevent damages to any of the actuating parts. The board that is pushed off of the spinner is transferred to a unit known as a "push-up" mechanism.

Spinner frame

The machine includes in part a pair of standards 380, 381 secured to the sub-frame by bolts 382, having overhung portions 385, 385a provided with bearings 383, 384 respectively, wherein is 20 journaled a shaft 386 provided at its ends with extensions 387 and 388 for a purpose to be further described. Upon the shaft 386 is securely mounted within the confines of the portions 385 of the supporting member 380, 381 a spinner frame 390, comprising a pair of end members 25 constructed to include hubs 391, 392 fixed to the shaft as by set screws or tapered pins 393, with radially disposed arms 394, at one end, and 396 at the opposite end, 180 (degrees) apart, terminating in a flanged portion 397, 398 adapted to have secured thereon by bolts 399, longitudinally disposed guide members 400, 401; the lowermost one 401 alternately becomes aligned with the "transfer" machine when the spinner is at rest.

The guide members 400, 401 are constructed and suitably proportioned to freely receive the form-supporting boards *B*, and retain same from radial displacement by cleats 402 secured to the guide members in a position to slightly overlie the longitudinal edges of the form-board *B*; said board being yieldably retained from longitudinal edges of the form-board *B*; said board being yieldably retained from longitudinal displacement by a device 405 including a pressure roll 403 that has a pin connection 404 within a

bifurcated end 406 of a rocker arm 407 that is pivotally mounted to a bracket 408 as at 409 secured upon the web member 410 of the guides 400, 401.

The web members are slotted as at 411 permitting of the roll 403 to be moved therethrough, and to contact with the form-board B upon entering or leaving the supporting guide, the pressure exerted thereon is attained by a tension spring 412 adjustable by a nut, co-acting with a screw 413 slidable in a bracket 414 secured to the guide members.

The rocking movement of the arm 407 upon which the roll is mounted is limited by an adjustable stop pin 416 threaded into a lug 417 integral with or otherwise secured to the bracket 408.

It is desired to provide a guard member at the receiving end of the spinner device, and for the purpose, a disc 420 is secured to the extension 387 of the shaft 386, having openings or notched portions in its peripheral surface to accommodate the entry of the form-boards B into the guides. A motion-checking device which as illustrated takes the form of a conventional mechanical brake 421; the drum of which is keyed to the extension 387 of the shaft while the friction elements are pivotally secured as at 426 to the standard 380; the free ends thereof being adjustably held together by an adjusting bolt which provides suitable frictional contact upon the drum surface to aid in retarding the motion of the spinner at the end of each cycle of operation.

Intermittent drive mechanisms

After withdrawal of the transferring pusher bars 359 and 365, the spinner 390 is made to revolve two and one-half times, through a spur gear 430 secured to extension 388 of the shaft 386, an intermediate gear 431 rotatable upon a stub-shaft 429 secured to the frame member 385a, and the large driving gear 432; the latter is keyed to the end of a short shaft 433 journaled into a bearing 434 that is carried upon the standard 381; the other end of the short shaft has secured thereon, one member 435 of a clutch device indicated generally by the numeral 436, having squared jaws 437 adapted to freely cooperate with a corresponding clutch member 438 that is mounted and splined for axial movement upon a short shaft 439 journaled into an elongated bearing 441 of a standard 442; its opposite end has fixed thereon a pinion 443 coaxing with a crank arm 444 having a rack portion 444a, held into meshing position therewith by a guide member 446 provided with suitable journaled lugs 447 bearing upon, and retained to the shaft 439 by a collar 448. The crank arm is reciprocated through the medium of a crank pin 449 secured to a pair of cranks 451, one of which is keyed to a driving shaft 452 that is synchronized with the transfer mechanisms, while the supplemental in crank has keyed therein an extension shaft 471 in co-axial relation with shaft 452.

The shaft 452 is driven through a gear reduction device 453 supported upon a standard 455, driven through miter gears 224a associated with the power shaft 224 that is driven through a sprocket 456a and chain 456b from a counter shaft that is transversely supported upon the frame standard of an adjacent machine.

The intermittent driving means for the spinner frame 390, is attained through a cam 451a having an 180 degree rise, and 180 degree swell,

secured to the shaft 471, its peripheral cam surface co-acting with a cam roll 451b that is urged into contact therewith through a spring 512 of the clutch device; said roll is secured by a pin 449a to a yoke member 446a. The lower end of the yoke is slotted as at 447a to override the said shaft, while its upper end is held into vertical alignment therewith through a slot 447b that overrides a guide post 439a provided with retaining collars 448a; the post is secured to a stationary member, such as the standard 381 of the machine frame.

A pair of curved arms 450, having pivotal connection to the yoke 446a as at 450a, are vertically extended therefrom, to actuate the arm 500 of the clutch yoke 506, through the pivot connection 505. The cam 451a is so timed relative to the crank pin 449 that when the pin, and arm 444, is starting its upward movement from bottom dead center, the arms 450 will have been moved downwardly, by virtue of the rise of the cam 451a acting upon the roll 451b, causing the clutch device to become disengaged. Simultaneously, the spinner will be locked and prevented from further rotation, through the actuation of the locking mechanisms upon disc 461 as described; and the transferring "cycle" will take place.

It will be noted at this juncture that the portion 518 of the arm 500 may be subjected to a non-return, or locked position, as shown in broken line (figure 245) by virtue of a safety latch device 521 to be later referred to, but in the present instance, it is to be understood that the stroke of the cam 451a is predetermined, and that during normal operation of the declutching mechanisms as herein described, the arm 500 is swung downwardly just short of the distance required whereby the device 521 can act thereon. At the instant the pin 449, and arm 444, has reached top dead center, to be reciprocated downwardly on the load stroke (reversing the direction of rotation of gears 430, 431, and 432), the disc 461 becomes released from the lock lever 466, and simultaneously the clutch device will re-engage for an interval of one-half revolution of the shaft 452; whereupon the cycle is completed.

During the first half of the cycle (the spinner 390 being at rest), a form-board B is moved longitudinally into the lowermost guide of the spinner frame by the pusher bar 359, while at the same time, the pusher bar 365 will eject a form-board B from the uppermost guide of the said spinner frame.

Spinner positive positioning

As best seen in Figure 6 the spinner shaft 386 has keyed thereon adjacent to the drive end, a positive positioning-disc 461 having formed upon its peripheral surface suitable notches 462 and 463 spaced 180 degrees apart, adapted to receive a lip portion 464 provided at one end of a rock lever 466 pivotally fulcrumed by a pin 467 secured to the frame portion 385a, the opposite end having a pivotal connection 468 with a cam rod 469, forked at its opposite end to override the cam shaft 471 which is rotated by the aforementioned cranks 451; said shaft has keyed thereon a cam member 472 having peripheral cam surfaces upon which a cam roll 473 coacts to actuate the cam rod 469, through a pin connection 474. The roll 473 is urged into contact with the cam 472 by means of a tension spring 476, one end of which is secured to an arm 468

of the rock lever 466, while the other end is secured to a pin 471 anchored to the frame standard 381. It will be noted that the cam member 472 is constructed with an inner dwell surface 479 of about 176 (degrees) and accordingly, the cam is provided with a timing adjustment for advancing or retarding the action of the notch-engaging lip 463. Such means include a recessed portion 481 in the side of the cam member body one-half the thickness thereof, having an arcuate slot 482, a segmental inset member 483 profiled to conform to the design of the cam, and bolts 484 coacting with the slot 482 to clamp the inset within the recess. The inset member 483 being shorter in length than the recess, adjustment may be made in either arcuate direction as required.

The spinner device 390 as herein shown is caused to rotate two and one-half times, whereupon the spinner becomes subjected to a rest period; which period is predetermined, and made positive by the action of the lock lever lip 463.

It is to be understood that the number of revolutions and the rate of speed thereof required to be made by the spinner, is contingent upon conditions pertaining to the solution or latex upon the forms A, and that the ratio of gearing may be easily and readily transformed.

It will also be noted that with each revolution of the cam 472, the locking lever will be actuated to alternately engage the notches 462 and 463 respectively, which corresponds to the position of the spinner, relative to the transfer machine when loading and unloading the form supporting boards B, into, and from the spinner frame, 35

Automatic safety clutch throw-out

As best seen in Figures 5 and 6 automatic safety clutch-control mechanisms include in part a cam 490 secured to the common cam shaft 471, cam roll 492 and cam bar 493, the latter being guided for vertical reciprocal movement through the medium of a slot (not shown) adjacent to one end which overrides the shaft 471, while its opposite end is slidable within a guide 496 secured to the frame 422, and has secured thereto a cam block 497 adapted to interlatch with a cam member 498 upon the free end of a connecting rod 499 pivotally co-acting as at 505 with one arm 500 of a rock lever 501 that is supported through a pin connection 502 upon a bracket 503 secured to the machine frame 381. The other arm 504 of the rock lever is constructed to form a yoke 506 provided with pins 507 that are carried on a block member 508 removably secured in the yoke. The pins 507 co-act with a shoulder 509 of a member 511 associated with the slidable member 438 of the clutch, to move same to the right as viewed in Figure 5 against the compression of a coil spring 512 that abuts a collar 513 secured on the shaft 439, to disengage the teeth of the clutch members when the connecting rod 499 is pulled downward by the cam rod 493 by virtue of the interlocked cams 497 and 498. The cam roll 492 is held into engagement with cam 490 by means of a tension spring 514 secured to a stationary member as indicated by the numeral 516, while the pendant rod 499 is urged into engagement position with cam rod 493 by 70 a tension spring 517 secured to the machine frame, and accordingly, when the pendant rod cam latch 498 is operatively engaged with the latch 497 of the cam rod 493, it will be moved downward to disengage the clutch members 75

through the action of cam 490 upon cam roll 492. While the clutch is thus disengaged, the end 518 of the rock lever 501 is acted upon by a locking device generally designated by the numeral 521 to prevent its upward return movement until the locking device has been released by the human hand of the operator.

As best seen in Figures 12 and 13, the device includes a dog 522 having an offset portion (not shown) fixed to a pintle (not shown) that is journaled on a supporting member 528 secured to the machine frame 422. A depending portion 529 carries a stop member 531 secured thereon to form a shoulder 532 at its lower end, relative to the extreme end 533 of the depending portion 529. The pintle has an extension 534 encircled by a torsion coil spring 536 one end of which is secured to a collar 537 fixed to the free end of the pintle, while the other end of the coil is anchored into the adjacent ear 527 of the supporting member. The device is positioned relative to the end 518 of the arm 500 so that the stop 531 which forms the shoulder 532, is yieldably urged against the side of the cam-arm 450, which in turn bears against the end-portion 518, by virtue of the torsion spring 536 and pintle 524, when the arm is operatively positioned relative to the engaged clutch, but when the arm has been pulled downward to the inoperative position, the dog is permitted to be further rotated to snap the shoulder 532 over the top thereof, to an extent which is limited by the depending portion 533 contacting the side of the arm 450, and accordingly, the arm 500 is held in this downward position, and will be prevented from returning to clutch-engaging position, until the safety locking device 521 has been manually released.

It will be noted that during the time that the pendant rod 499 is in the downward position, that its latching cam 492 has been positioned too far downward to be engaged by the cam rod latch 497 which is being continuously reciprocated, and at each upward stroke of the cam rod 493, 45 the cam 497 pushes the pendant rod 499 out of its path by means of the association of the inclined surfaces 541, 542 of the rod 499 and cam 497 respectively.

A guide member 543 secured to the frame 422 serves to keep the pendant rod 499 in vertical alignment with cam rod 493 at all times.

Automatic safety mechanisms

If for any reason a jam should occur in the spinner apparatus such as, for example, an incoming or an outgoing form supporting board B not clearing the ends of the guides 400, 401 of the spinner; i. e.: in the latter it may not be pushed into the guide far enough, or in the former it may be pushed too far and prevent rotation thereof, a safety mechanism is incorporated in the machine to prevent damage to any of the actuating members. With this in mind, during normal operations of the driving mechanisms as before described, a stop-finger is yieldably swung through a space, such space being that which is transversely of the path of travel taken by the board B just prior to its entry to the spinner guide from the transfer machine, and another stop-finger is made to function in a like manner relative to the path of travel taken by the outgoing board B when being ejected from the spinner.

These fingers are timed to be actuated into said path about 80 (degrees) in advance of the

spinner release lever 466. As best seen in Figures 2, 5, and 6, one of the fingers designated by the numeral 590 of a rock-lever 591 pivotally connected to a bracket 592 secured to the frame 385, is actuated through a pin connection 593 of a rod 594 which is pivotally connected as at 595 to the end of a rock-lever 597 secured to a common rock shaft 598 journaled into bearings 599, 601, 602 carried by standards 603, 604, 606 respectively, which are mounted upon and secured to the sub-base. The other finger 607 of a rock lever 608 pivotally connected to a bracket 609 by pin 611 secured to the frame, is actuated through a pin connection 612 of a rod 613 which is pivotally connected as at 614 to the end of a rock-lever 616 secured to the rock shaft 598 intermediate to its ends.

The rock-shaft 598 is yieldably oscillated through the medium of a vertically disposed arm 617 (having an extension 518 to be presently described) secured upon its opposite end, having a pivotal connection 619 with a cam rod 621; said rod being slotted at the opposite end to override the cam shaft 471, by a heavy tension spring 626, one end of which is secured to the cam bar 621 as indicated at 627, the other end having a connection with a pin 628 of a supporting member 629 secured to the machine standard 422.

At this juncture it will be interesting to note that due to the novel mechanical hook-up of the mechanisms just referred to, that the time period of oscillations of the shaft is controlled by the position of the cam roll 622 relative to the cam surface 623, i. e.: the roll is held away from said surface by the fingers, through the several mechanisms, when the movement of either of the fingers toward the path of the board B is obstructed, but under normal operating conditions the roll 622 is made to follow the cam surface 623 through the medium of the heavy tension spring 626, whereupon the shaft 598 is caused to function continuously.

At the upper end of the extension 618 of arm 617 is pivotally connected by a pin 631, a cam bar 632 having its opposite end slidably supported in a bracket 633 secured to the frame 422. The bar 632 is suitably positioned adjacent to one edge of the aforementioned pendant rod 499, which carries at its lower end, the cam latch 498, to have a cam block 634 that is fixed thereon, co-act to dislodge the interlatching engagement of cam latch 497 and cam latch 498 when the bar is permitted to be moved to the right as viewed in Figure 5 and through (as before stated) the arm 618, cam rod 621 and tension spring 626.

From the foregoing description, including the clutch safety throw-out mechanisms, it will be seen that under normal operation of the parts, i. e.: there being no obstructions in the spinner apparatus, the pendant bar 499 will be acted upon, to disengaging position with cam rod 493 at each oscillation of the rock-shaft 598, and that the clutch 436 may retain its normal function, so long as the rock-shaft 598 is permitted to function.

Counterbalancing mechanism

It will be noted that when the board is pushed into the spinner frame, the mechanism is out of balance due to board being off center. When the mechanism spins, centrifugal force will cause destructive forces to be set up in the whole unit unless the board is counterbalanced during the spinning cycle. At the same time, when no board is in the spinner frame, the counterbalance must

be kept out of action to prevent destructive strains in the mechanism. The device is so constructed, that if a board is pushed into the spinner frame to be spun around, the counterbalance is connected to the spinner frame and therefor counteracts the centrifugal forces set up by the board and, when no board enters the spinner frame the counterbalance is kept out of action during the spinning cycle. The mechanism is

10 worked out as follows:

Attached to spinner shaft 386 on the patent drawings is sprocket 801 on the blueprint. Chain 802 connects sprocket 801 to sprocket 803, which in turn is keyed to shaft 804. Shaft 804 is supported by bracket 805. Chain 802 is kept tight by idler sprocket 806, lever 807 and rods 808. Sprocket 809 is keyed to shaft 804. Chain 810 connects sprockets 809 and 811 and is kept tight by idler 812. Bell lever 813 and rod 814. Sprocket 811 and straight jaw clutch 815 are one unit. The foregoing parts connect the spinner frame to the counterbalance shaft 816 which is supported in bracket 817. Clutch 815 can revolve freely on shaft 816. Mounted on shaft 816 and also 15 slidably splined to it is the other half of the clutch 818, backed up by spring and collar 819 and 820 respectively. Keyed to shaft 816 is disc 821. Disc 821 is fastened to counterbalance disc 822 by means of bolts. Disc 822 also supports 20 the counterbalance weight 823 which is adjustable radially on rod 824 by means of nuts 825. Disc 822 is keyed to shaft 827 which is supported by bracket 817. Attached to shaft 827 is arm 829. Also mounted in bracket 817 is disc 830 25 which holds roller 831 thru pin 832. Disc 830 is keyed to shaft 833. Fastened to disc 830 is sprocket 834 which in turn is connected to sprocket 835 thru chain 836. Chain 836 is mounted on shaft 837 supported by brackets 838 30 and 839. Mounted on shaft 837 is cam 849 with an adjustable lobe 841, the cam keyed to the shaft. Also keyed to shaft 837 is sprocket 842. 35 Sprocket 843 is connected to sprocket 843 thru chain 844. Sprocket 843 is driven by reduction box 845 thru shaft 846. Reduction box 845 also drives the transfer mechanism which slides the board into the spinner frame. Since the transfer and spinner reduction boxes are driven from a common shaft, they are always in time with one another, and therefor the interrelationship between the 40 spinner, transfer and counterbalance can be maintained at all times. By following the mechanism thru it will be seen that the spinner shaft 386 rotates the counterbalance when the jaw clutch 818 is engaged with 815. Therefor if the spinner shaft drives the counterbalance, it can 45 be seen that it is possible to have the board in the spinner frame and the weight in opposition so that the eccentric forces present during revolution can be neutralized. Following the cycle 50 of a board thru the spinner frame, the operation of the mechanism is as follows:

When the board is pushed into the spinner frame by the transfer arm, the leading edge of the board comes in contact with arm 847 pinned to shaft 848 supported by brackets 849 and 849a. Lever 850 is also pinned to shaft 848. Attached 55 to the end of lever 850 thru a stud is link 851. The other end of the link 851 is attached to latch 852 by means of a stud. Thus when the board 60 comes in contact with the arm 847 it lifts the latch 852. Latch 852 is ordinarily in contact with yoke 853 which controls the motion of jaw clutch 818. When the board is being pushed into 65 the spinner frame, cam 840 is so timed with the 70

75

stroke of the transfer arm which moves the board, that the lobe 841 of the cam 840 comes in contact with the roller 854 fastened to lever 855 thru stud 858 for about one third the stroke of the board. Lever 855 is pinned to shaft 857 supported by bracket 858; yoke 859 is also pinned to shaft 857; therefor when roller 854 comes in contact with lobe 841 it causes yoke 859 to move away from latch 852 about one sixteenth of an inch. It must be noted that the yoke 859 moves away from the latch 852 just before the board comes in contact with arm 847 so that the latch may be lifted without hindrance. As long as the latch 852 is lifted out of contact with yoke 859, it is possible for spring 820 to push jaw clutch 818 into mesh with jaw 815 when roller 854 rolls off lobe 841 and so connect the spinner frame with the counterbalancing mechanism as previously described. At the beginning of every spinning cycle it will be noted that the board is in the lower half of the spinner frame and therefor it will be necessary for the counterbalance weight 823 to be opposed or on the top of the circle. By means of a mechanism to be described subsequently, the counterbalance is in this position at the beginning of every spinning cycle and with the spinner frame makes two and one half revolutions during each spinning cycle. At the end of the spinning cycle it is necessary to disconnect the counterbalance from the spinner frame and this is accomplished by cam lobe 841. For each spinning cycle, cam 840 makes one revolution and therefor when lobe 841 comes in contact with roller 854 just before the end of the spinning cycle, it pushes jaw 818 out of contact with jaw 815 and so disconnects the spinner frame from the counterbalance weight 823. While a board is being pushed into the spinner frame, weight 823 must be returned to the top of the circle since, at the end of the spinning cycle the weight ends at the bottom of the circle. This is accomplished as follows:

Disc 830 is keyed to shaft 833 supported in bearing 861 which is part of bracket 817. Sprocket 834 is rigidly attached to disc 830 and is connected sprocket 835 in a one to one ratio by means of chain 836. Sprocket 835 is keyed to shaft 837 which is supported by brackets 839 and 838. Since cam 840 is also attached to shaft 837 it is timed with disc 830 in a one to one ratio. 50 Arm 829 is keyed to shaft 827 which in turn is keyed to weight 823. Attached to disc 830 is a stud 832 supporting a roller 831. The mechanism is so timed that when the end of the spinning cycle has been reached and the counterweight 823 at the bottom of the circle and therefor weight 823 is also hanging directly downward, roller 831 comes in contact with arm 829 and lifts the counterbalance to the upright position in one half revolution. One complete revolution of the disc 830 corresponds to one board cycle or twice a spinning cycle since in one board cycle, the board must be pushed into the spinner and then put thru the spinning cycle. Since a board which has been spun is pushed out of the spinner frame on the top half of the frame while a board is being pushed into the lower half of the frame it will be understood why the board cycle does not include pushing the upper board off in addition to the above mentioned operations. 70 When roller 831 comes in contact with arm 829,

it must be noted that shaft 833 is not coaxial with shaft 827 but is located approximately three quarters of an inch above it, and therefor roller 831 contacts arm 829 at about one and one half inches from the end of the arm. When arm 829 reaches the top of the circle, roller 831 rolls off the end of the arm and therefor leaves the arm 829 and consequently weight 823 at the top of the circle. Also, shaft 833 is located in a horizontal plane about one and one half inches away from the axis of shaft 827 so that during the spinning operation, arm 829 cannot come in contact with roller 831. It will be noted that the spinning operation occurs while roller 831 is on the downward stroke, while on the upward stroke of roller 831, the arm 829 is lifted. As noted above, the weight 823 is left at the top of the circle. In order that it may be held in this position and not fall back to the bottom of the circle where it would be out of position for the spinning operation, the end of rod 824 is notched as at 863. When the notch reaches the top of the circle, roller 864 is pushed into notch 863. Roller 864 is supported in lever 865 by means of pin 866. 25 Lever 865 pivots on shaft 867 supported by bracket 868 fastened to transfer frame 867a. Pinned to shaft 867 is yoke 869 which forms a rigid backing for spring 870. Spring 870 surrounds spring rod 871 and the spring is put under compression 30 by means of a washer bolstered by a cotter pin thru the rod 871. Locknuts 872 regulate the position of roller 864 with respect to the notch 863 on the counterweight shaft 824. The roller is so positioned as to just hold the counterweight 35 from falling of its own accord when it is at the top of the circle and yet be free enough to offer no substantial impediment to the motion of the counterweight when it is in revolution. Thus it can be seen that the counterweight is always 40 returned to the top half of the circle at the end of each spinning cycle and held there in readiness for the ensuing spinning cycle.

It is also necessary to describe the action of this mechanism in case a board is not pushed into the spinner. Inasmuch as it has been previously stated what happens when a board is pushed into the spinner and what sequence of mechanisms takes place it will be noted that the entire action of placing the counterweight in action is controlled by arm 847. When arm 847 is lifted by the board as it enters the spinner frame, the counterweight is connected to the spinner frame. Therefor it follows that if the arm is not lifted, the counterweight will not be connected and therefor will remain at the top of its circle of revolution. Hence no unbalanced weight will be spun which might cause damage to the spinning mechanism.

What is claimed is:

In a machine of the character described, a cylindrical spinner, a shaft extending longitudinally through the center thereof, form board guides extending longitudinally along the periphery of the spinner, a form board slidably mounted in each guide and capable of being ejected by the entry of a new board, forms mounted on the boards and extending radially with respect to the cylinder, and automatic means for spinning and stopping the cylinder.
